UNITED STATES PATENT OFFICE.

AUGUSTUS LIESE, OF SOUTH LANCASTER, MASSACHUSETTS.

WRENCH.

1,127,786.

Specification of Letters Patent.

Patented Feb. 9, 1915.

Application filed April 16, 1914. Serial No. 832,363.

To all whom it may concern:

Be it known that I, AUGUSTUS LIESE, a citizen of the United States, residing at South Lancaster, in the county of Worcester and State of Massachusetts, have invented a new and useful Wrench, of which the following is a specification.

This invention relates to a wrench of that type in which a head is provided having one fixed jaw at one edge thereof and a movable transverse jaw slidably mounted on the head to coöperate with the fixed jaw, a handle being provided and extending out of the head at the other side for reciprocating the movable jaw. As heretofore constructed as far as I am aware, wrenches of this type have been so made that the two jaws would not close together fully and the handle has necessarily been pivoted to the head. This pivoted connection of the handle has always resulted in giving a comparatively short leverage for the size of the head and thus a comparatively small amplitude of motion, while the pressure has been transmitted from the handle to the jaw through pivot pins and the like. Moreover there has been no way of setting the movable jaw into position against the nut or bolt head except by swinging the handle on its pivot. This invention is designed to do away with these difficulties, present a more simple, practicable and efficient article of this general type, and especially to provide for transmitting the pressure by an internal part of the handle so that the pivot pins do not receive or transmit any pressure.

Reference is to be had to the accompanying drawings in which—

Figure 1 is a plan of a wrench constructed in accordance with this invention showing the jaws open; Fig. 2 is a similar view with the front of the head removed and showing the handle in position to place the movable jaw against a nut; Fig. 3 is a similar view partly in section showing how pressure is transmitted to the sliding jaw from the handle, and Fig. 4 is a sectional view on the line 4—4 of Fig. 1.

This wrench is illustrated as comprising three main parts, a head A, a slide B and a handle C, the latter being connected with the slide by a link D. The head is shown as consisting of a casting cored out so as to provide a large hollow space for receiving the end of the handle and the slide. This head is provided with an integral stationary

jaw a and with guides a' transverse thereto and extending under the stationary jaw. Openings a² at the ends of these guides are provided for allowing the slide to extend therethrough. On the slide B is a jaw b corresponding in shape and other characters with the jaw a. The slide B has guide grooves b' by which it is guided in the guides a'. It is provided with a passage b² therethrough and in this passage the link D is pivoted. The other end of the link extends out through the edge of the slide and is pivoted by a pin E to the handle. This pivot pin is located substantially in the plane of one edge of the slide. In the end of the slide is a notch b³ having edges b⁴ transverse to the direction of the motion of the movable jaw. The handle is provided with a pair of slanting surfaces c with their ends almost at right angles to each other, designed to engage the surfaces b⁴ as the handle is swung. At the ends of these surfaces are rectangular notches c² which receive the corners of these surfaces in the extreme positions of the handle. The handle extends through an elongated opening in the end of the head A and has free play therein.

In the operation of the device the jaws are opened by swinging the handle in one direction and then the fixed jaw is put against the side of a nut or bolt head. The movable jaw can then be moved along by the handle so as to bring it into contact with the opposite side of the nut. (Compare Figs. 1 and 2). It will be noticed that in accomplishing this motion the handle can be moved along by a parallel motion without swinging it on any pivot. In this way the jaw can be brought up firmly against the bolt head before any pressure is applied. Now in order to apply pressure the handle is swung to the right into the position shown in Fig. 3 where its edge comes against the edge a⁵ of the opening and that surface acts as its pivot or fulcrum. In this way it will be seen that this fulcrum is removed as far as possible from the jaw and consequently a comparatively great amplitude of motion is secured. At the same time there is no pivot pin on which the pressure comes and no weak point that is likely to break away in practice. Particular attention is directed also to the way in which the motion is transmitted positively from the end of the lever to the movable jaw thus securing a

very effective leverage. I do not depend upon the link D for transmitting this motion, the function of this link being merely to hold the jaw and handle together against displacement. The positive operating action is secured by the actual engagement of the slanting surface *c* with the surfaces *b*⁴ forming the edges of the notch in the movable jaw. This shows clearly in Fig. 3. In 10 this way it will be seen that a great leverage is secured, practically the entire length of the head being taken up by the short arm of the lever. The notches *c*² for receiving the edges of the walls *b*⁴ of the passage *b*² also 15 act as positive stops at the ends of the motion of the movable jaw.

Although I have illustrated and described only a single embodiment of the invention, I am aware of the fact that modifications 20 can be made therein by any person skilled in the art without departing from the scope of the invention as set forth in the claims. Therefore I do not wish to be limited to all the details of construction herein shown but 25

What I do claim is—

1. In a wrench, the combination with a head having a fixed jaw thereon and a transverse guide and a movable jaw slideable along said guide, of a handle projecting into said 30 head pivotally connected with the movable jaw, said head having an elongated slot through which the handle projects, the edges of said slot constituting fulcrums for the handle.
2. In a wrench, the combination with a head having a fixed jaw thereon, and a movable jaw slidably mounted in the head, said head being provided with an opening in the end opposite said jaws, of a handle freely mov- 35

able in said opening whereby the edges of 40 the opening constitute fulcrums for the handle, and means whereby the end of said handle positively operates the movable jaw.

3. In a wrench, the combination with a 45 slideable jaw, having a notch in one edge thereof provided with front and rear surfaces substantially transverse to the direction of motion of the slideable jaw, of a link pivotally connected with said movable jaw and a handle connected with the link and 50 having an end projecting into said notch, said handle having two surfaces at substantially right angles to each other for engaging said front and rear surfaces and positively pushing the jaw in either direction. 55

4. In a wrench, the combination with a slideable jaw, having a notch in one edge thereof provided with front and rear surfaces substantially perpendicular to the direction of motion of the slideable jaw, of a 60 handle pivotally connected with said movable jaw and having an end projecting into said notch, said handle having two end surfaces at an angle to each other for engaging said front and rear surfaces and positively pushing the jaw in either direction, the point of pivotal connection of the handle with the jaw being substantially on the line of the edge thereof, said handle having notches beyond said surfaces for receiving 65 the edges of the notch.

In testimony whereof I have hereunto set my hand, in the presence of two subscribing witnesses.

AUGUSTUS LIESE.
